ELECTROLYTIC DEPOSITION APPARATUS.

APPLICATION FILED APR. 7, 1903.

NO MODEL.

UNITED STATES PATENT OFFICE.

WILLIAM J. JORY AND JOSEPH H. JORY, OF SAN FRANCISCO,
CALIFORNIA.

ELECTROLYTIC DEPOSITION APPARATUS.

SPECIFICATION forming part of Letters Patent No. 757,557, dated April 19, 1904.

Application filed April 7, 1903. Serial No. 151,492. (No model.)

To all whom it may concern:

Be it known that we, WILLIAM J. JORY and JOSEPH H. JORY, citizens of the United States, residing at San Francisco, in the county of San Francisco and State of California, have invented a new and useful Electrolytic Deposition Apparatus, of which the following is a specification.

This invention relates to electrolytic deposition apparatus.

The object of the invention is in a simple, rapid, thoroughly efficient, and practical manner to extract metals from slimes, sand, and solutions in which they are contained.

With these and other objects in view, as will appear as the nature of the invention is better understood, the same consists in an electrolytic apparatus for depositing and accumulating gold, platinum, silver, quicksilver, copper, antimony, tin, lead, and other metals from fluids in which they may be held in suspension or in solution by electrolytic action alone or aided by other agencies.

In the accompanying drawings, forming a part of this specification, and in which like numerals of reference indicate corresponding parts, there are illustrated two forms of embodiment of the invention, each capable of carrying the same into practical operation, it being understood that the elements therein exhibited may be varied or changed as to shape, proportion, and exact manner of assemblage without departing from the spirit thereof, and in the drawings—

Figure 1 is a view in perspective of an apparatus constructed in accordance with the present invention. Fig. 2 is a view in transverse section. Fig. 3 is a view, partly in elevation and partly in section, of a slightly-modified form of a portion of the apparatus. Fig. 4 is a detail view of a slightly-modified form of bottom for the apparatus. Fig. 5 is a perspective detail view of one of the supports or bearings for the shafts of the electrodes. Fig. 6 is a detail view in perspective of an end of one of the electrode-shafts with a collar for maintaining electrical contact with the mercury contained in the bearings for the shafts.

The apparatus consists of a trough-like table 1, which is to be of such capacity that the flow of the solution, the water carrying metals in suspension accompanied by sands, or any other fluid holding the metals to be recovered shall form a shallow stream while flowing at such a rate as to carry off the sands contained in the fluid. At the bottom of this trough is laid a plate or plates 2 of copper, silvered copper, or other suitable metal, fitting closely to the sides thereof and extending from end to end of the table. The surface thus presented may be plain or corrugated, according to the character of work to be done, and constitutes one pole of the apparatus. In some instances the bottom of the apparatus may be provided with riffles or depressions 3, as shown in Fig. 4, to contain mercury, the riffles being electrically connected to constitute the electrodes of the apparatus.

Secured to the sides of the table are two supports 4, constituting a frame upon which are supported electrodes 5, which may be of the form shown in Fig. 1 or that shown in Fig. 3. These electrodes may be made of any suitable metal or of carbon or of any conducting fabric, either rigid or flexible, and are secured to the metallic or carbon bars 7, mounted for rocking movement in bearings 8 on the upper edges of the frame 4. Instead of connecting the electrodes rigidly with the shafts or bars 7 these may be loosely mounted to swing thereon, as shown in Fig. 3. Each of the shafts 7 carries near each end a collar 10, as shown in detail in Fig. 6, the collars being held upon the shafts by set-screws or other equivalent form of fastening device. The collars work in bearings 8, the bearings, in effect, constituting sockets to present receptacles for mercury, thus at once lessening the friction of the bearing and forming an electric conductor.

Extending along both sides of the exterior of the frame near its upper edges and in contact with the bearings 8 are copper rods 11, said rods forming a means by which the electric current is conveyed to the electrodes, and extending along both sides of the exterior of

the frame near its lower edges are copper rods 12, which are electrically connected with the copper plates 2 by set-screws 13, which pass through the rods 12 and into the plates, these 5 latter rods operating to convey an opposite electric current into the plate-electrodes 2.

For the suspended electrodes 5 (shown in Figs. 1 and 2) may be substituted electrodes 6, as shown in Fig. 3. The electrodes 6 are 10 the preferred form, being balanced to present but slight obstruction to the passage of sands and other solids contained in the flow of liquid, and are adapted, when their lower parts have become so worn, abraded, corroded, or 15 overweighted as to become unserviceable, to be reversed. The electrodes of both forms being pivoted for free movement at the top of the sluice-box are adapted to rest at their lower ends substantially on the surface of the 20 stream flowing through the sluice-box and may properly be described as floating thereon.

The collars 10 are each provided with one or more adjustable stops 14, which may be set to prevent the electrodes from coming into 25 such close proximity to the plate-electrodes 2 or the riffle-electrodes 3 in the bottom of the trough as to make a short-circuit or, on the other hand, from swinging so far above the plate-electrodes as to lower the efficiency of 30 the apparatus.

At each corner of the table is placed an adjusting-screw 15, by which the level of the apparatus may be changed to give it the greatest possible efficiency by increasing or diminishing the rate of flow to carry off the lighter or heavier sands of the various ores or to cause a greater or less flow of the fluids being acted upon by the electric current.

In using the apparatus as above described 40 a stream of water in which metal that is to be recovered is present in one of the forms hereinafter more specifically disclosed is caused to flow through the apparatus and is subjected to electrolytic action through the electrodes 45 above described either aided by chemical agencies which vary with the metals to be recovered or unaided by any other agency. The depth of the stream containing the metal and its rate of passage through the accumulator 50 will depend upon a variety of conditions and will vary with the nature of the metal to be recovered and the form in which it is present in the stream passing through the apparatus. The current employed is to be of such density 55 and tension on the electrodes as to cause the various electrochemical and other reactions necessary to produce the electrolytic and electrolytic amalgamating effects desired and is always adjusted to the metal to be deposited 60 and to the special chemical forces which hold it in the solution. Where electrolytic amalgamation is employed, the strength of the current will be adjusted according to the strength of the chemical forces holding the mercury in 65 combination and to the intensity required to

decompose a small quantity of water, so as to produce a hydrogen amalgam by the combination of the hydrogen set free by the decomposition of the water with the mercury freed at the same time, or the current will be adjusted to effect sufficient decomposition of sodium chlorid, if that salt be present, to produce a sodium amalgam. In all cases, except those hereinafter named, the plates 2 form the cathodes and the swinging electrodes the 70 anodes of the apparatus. The bars 11 are connected by a cross-rod 16, to which is connected a binding-post 17, with which is connected the positive conductor, and the bars 12 by a cross-bar 18, with which is connected a binding-post 80 19, connecting with the negative conductor.

When natural sands are passed through the apparatus, these are to be so screened from the coarser gravel as to prevent any mechanical injury to the apparatus. Metallic mercury 85 in exact quantities to form a plastic amalgam is introduced into the sands before entering the accumulator, and sufficient sodium chlorid in solution is added to form a sodium amalgam under the electrolytic forces of the apparatus. 90 Under such a procedure, with an ample electric current properly introduced, sufficient water and sodium chlorid is decomposed to form a hydrogen-sodium amalgam on the cathode-plate that is very effective in securing and accumulating all the metallic particles contained in the flow. In the absence of salt a hydrogen amalgam is formed which is only less efficient than the sodium amalgam.

In the procedure governing the deposition 100 of the precious metals from the flow proceeding from stamp-batteries the following courses are pursued: In the common methods of the recovery of gold and silver in stamp-batteries and on the tables over which the pulp from the batteries passes it is usual for the purpose of amalgamation to introduce into the batteries at certain intervals such quantities of metallic mercury as may be necessary to produce a proper amalgamation of the gold 105 and silver contents of the ores operated on. Platinum existing in such ores unalloyed is not subject to normal amalgamation and under the common methods is lost. Great losses also occur in the slimes and floured 110 amalgam produced in the stamp-mill. To prevent such losses in platinum, gold, and silver, we introduce into the batteries a solution of some soluble mercuric salt, such as mercuric nitrate or mercuric chlorid, in such 115 proportions with the metallic contents of the ore as will form an amalgam of such metals in so plastic a form that it may easily be removed from the plates and yet of such firmness that it will not be carried off in the flow 120 of water and sands. When the mercury solution is so introduced and electrolyzed by means of the current supplied by the electrolytic apparatus, the mercury set free is deposited upon the cathodes of the apparatus 125 130

and all the precious metals contained in the flow are recovered by amalgamation with the mercury so deposited. The salts of the precious metals are decomposed simultaneously with the mercury salts and sodium chlorid, if the latter is present, and a hydrogen-sodium amalgam is produced. The precious metals present as such in the flow will be more readily recovered by the mercury deposited on the cathodes by electrolysis than when the cathodes are coated with mercury by other means. The action of the apparatus is substantially similar to that just described when metallic mercury is wholly or in part introduced into the stamp-batteries with sodium chlorid. The density and tension of electric current required in performing these and all other actions and reactions of the electrolytic accumulator may be readily calculated by any skilled electrometallurgist by taking into consideration the various solutions to be decomposed and the several depositions to be made.

Great difficulty and losses occur from the slimes produced in amalgamation milling operations whether these are or are not combined with cyanid or other leaching processes. To obviate this, we proceed in the following manner: When the ore is passed through the stamp-batteries or other pulverizers either without or with the introduction of the chemicals above named, or of others, such as potassium cyanid, which are sometimes employed to facilitate amalgamation, the sands, pulp, and slimes produced are passed through an electrolytic deposition apparatus, as above described, and having the lower plates so electrically connected as to form cathodes of the apparatus. Under these conditions all those particles of metals mixable with water and held in suspension or in solution will be deposited and accumulated on the lower plates; but there are generally produced in stamp-batteries a quantity of fine slimes and powdered amalgams combined with graphite, talc, and other ingredients of the ores, which form a greasy scum on the surface of the flow that carries away with it very considerable quantities of the precious metals impossible to amalgamate in the ordinary way. We therefore cause the stream after its passage through the electrolytic apparatus, as above described, to pass through another apparatus having for its purpose the extraction of the precious metals from the slimes and floured amalgam carried on the surface of the flow. This form of the apparatus coincides in its general design with that already described, but has its electrodes electrically reversed, so that what were before the anodes of the apparatus now become the cathodes, and vice versa. The floating electrodes in this case are formed of copper or silvered copper or other proper material, while the lower plates, which have now become the anodes of the apparatus, may be made of carbon or other good conducting ma-

terial not easily corroded by the substance produced during electrolysis. By the forces of this electrically-reversed apparatus mercury is deposited on the floating cathodes and all the precious metals contained in the slimes on the surface of the flow are recovered by amalgamation with this mercury.

In the application of the electrolytic deposition apparatus to the recovery of metals from their flowing solutions the following procedure is taken: The ores having been pulverized and leached, the solutions obtained are passed from the leaching-tanks into the deposition apparatus in such quantities that the electric current provided may produce a perfect deposition of the contained metal or metals in a simple metallic form. The length and width of the deposition apparatus, the rate of flow of the solution, and the dynamic forces of the electric current are all factors to be taken into consideration in the adjustments to be made to produce the desired results. Gold, silver, and copper are among the metals most readily deposited and accumulated from their solutions by the processes of the electrolytic apparatus, and the cathode-plates being coated at the beginning of the operation with a dressing that is at once efficiently-conductive and non-adhesive, such as graphite, the accumulated metals may be removed as pure, metallic sheets as often as convenient after deposition. Metallic quicksilver is also readily deposited from its solutions by the processes of the electrolytic apparatus. In this case the cathode-plates at the bottom of the deposition-tanks are preferably of polished iron or steel, and the apparatus is adjusted to such an incline that the deposited metal flows off with the exhausted solution, which, passing over an iron tank, the mercury by its superior gravity falls to the bottom, while the solution passes over into a sump. The iron tank into which the mercury falls is electrically connected with the negative pole of the electric circuit, while a perforated anode suspended in the fluid above the metal is connected with the positive pole. The electric current is introduced in such density and tension that under the conditions described no solution of the metal is possible by the solvent with which it may be in contact. A stop-cock is provided at the bottom of the metallic tank, so that the quicksilver may be drawn off at intervals in a pure state without waste of the metal or of the solvent.

In the recovery of lead from its solution obtained from ores in such chemical condition as prevents its easy deposition in the metallic state it is provided to deposit this as an oxid in the following manner: An electrically-reversed deposition-tank is provided having iron or copper anode-plates at the bottom of the apparatus dressed with graphite. The lead solution passing through the apparatus deposits its lead contents when proper adjust-

ments of the electric current have been made, as a lead peroxid, which may be removed from time to time, as in the case of metallic deposits. It is also provided that when two 5 or more metals existing in the solution are to be deposited from the one flow that two or more deposition-tanks are set, the one to follow the other and through which the solution flows, the electric current so adjusted as to 10 deposit the one metal requiring the least electrical energy for its deposition in the first apparatus and the one requiring a higher degree of energy next, and so on until all the metals are recovered in the one operation.

15 Having thus described the invention, what is claimed is—

1. An apparatus of the character specified, comprising a sluice-box and electrodes swinging on horizontal axes and adapted to float on 20 the surface of a stream passing through the box.
2. An apparatus of the character specified, comprising a sluice-box and electrodes swinging freely on axes disposed transversely of the 25 sluice-box.
3. An apparatus of the character specified, comprising a sluice-box, bearings supported thereby and containing mercury, horizontal rods or shafts working in the mercury, and 30 freely - swinging plates, forming electrodes supported by the shafts.
4. An apparatus of the character specified, comprising a sluice - box, bearings carried thereby and containing mercury, shafts having collars working in the mercury, and electrodes supported by the shafts.
- 35 5. An apparatus of the character specified,

comprising a sluice-box, and reversible swing-ing electrodes supported thereby.

6. An apparatus of the character specified, 40 comprising a sluice-box, swinging electrodes supported thereby, and adapted to rest on the surface of the flow through the box and means for limiting the range of movement of the elec-trodes.

45 7. An apparatus of the character specified, comprising a sluice-box, bearings supported thereby and containing mercury, shafts having collars working in the mercury, stops carried by the collars, and reversible electrodes car-ried by the shafts.

8. An apparatus of the character specified, comprising a sluice-box, plates disposed on the bottom thereof, bearings containing mercury supported by the box, shafts having collars 55 working in the mercury, plates swinging on said shafts and forming electrodes, and elec-trical connections in circuit with the bearings and with the plates.

9. An apparatus of the character specified, 60 comprising a sluice-box, transverse shafts ro-tatably mounted at the top of said sluice-box, and plates having oppositely-curved ends sup-ported midway of their ends upon said shafts and forming reversible electrodes.

65 In testimony that we claim the foregoing as our own we have hereto affixed our signatures in the presence of two witnesses.
